Jeffrey, Keeler, Taylor & Co.

ATTORNEY

UNITED STATES PATENT OFFICE.

WALTER SCHENKER, OF WINTERTHUR, SWITZERLAND, ASSIGNOR TO BUSCH-SULZER BROS.-DIESEL ENGINE COMPANY, OF ST. LOUIS, MISSOURI, A CORPORATION OF MISSOURI.

FUEL ENGINE VALVE.

Application filed September 18, 1925, Serial No. 57,256, and in Switzerland December 15, 1924.

The invention is a safety feature for the fuel injection valves of Diesel and other injection type engines, particularly for fuel valves in which the valve proper, its closing spring and its lifter arm are enclosed in the valve housing. Excessive pressure from explosions occurring in such a housing or transmitted to it from the engine combustion space is likely to burst or shatter it, causing injury, and the object of this invention is to confine any such excessive pressure to the lower or inner part of the housing, which is stronger because reinforced by surrounding structure.

To this end, the invention consists in the application of a device in the nature of a check valve to the passageway between the inner and outer parts of the valve housing after the general manner indicated in the accompanying drawing, which represents an axial section through an ordinary type of fuel valve having the invention applied to it.

The valve shown is intended for the injection and atomization of fuel oil by means of high pressure air and the housing is accordingly supplied with a fuel line connection 1 and an air connection 2, both delivering, as indicated, to the inner part or chamber of the valve housing which chamber communicates with the spray nozzle when the valve needle 3 is lifted from its seat. The lower end of the valve needle is surrounded by a mixing sleeve 4 to assist in the mixture of the air and oil in transit to the nozzle, but this mixing device, it will be understood, is merely an incident to the use of high pressure air for fuel spraying purposes and with other types of valves may be omitted. The part of the valve housing between the fuel and air connections and the spray nozzle is shown as water-jacketed, although this also is not essential, and is seated in an appropriate opening in the cylinder head 5, being understood to be clamped therein as usual.

The valve needle 3 extends from the inner part of the valve housing into the upper or outer part wherein it is provided with a collar 6 and subject to the closing pressure of a spring thrusting against the collar. The lifter arm 7 engages the underside of the collar to open the valve in the usual way

and the lifter shaft 8 will be understood to be provided with a suitable packing where it enters the housing; this does not appear in the drawing. Midway between the outer and inner parts, the interior space of the valve housing is divided by means of a two-part box-form bushing, the parts of which, marked 9 and 10 respectively, are threaded together and to the valve housing, being introduced into position through the outer open end of the housing before the cap 11 has been clamped in place. The valve needle reciprocates within this bushing and inside the bushing it is provided with a short sleeve 12 snugly, but slidably fitted thereon, and capable of slight axial play in the interior chamber of the bushing. On the occasion of excessive pressure in the inner part of the valve housing, the rush of gas through the relatively restricted chamber, or passageway of the bushing, presses the sleeve 12 outwardly against the outer member of the bushing and thus closes the crevice between the same and the valve needle so as to prevent transmission of dangerous pressure to the outer part of the housing. It will be apparent that the same effect can be produced by other instrumentalities having the same mode of operation as the annular member or sleeve just referred to, but the structure shown is very simple and efficient and is preferred on that account.

The following is claimed:

- An injection valve for injection type engines comprising a housing containing the movable valve member and a check valve between the inner and outer parts of said housing adapted to prevent transmission of dangerous pressure from the former to the latter.
- An injection valve for injection type engines comprising a housing for the movable valve member, which housing encloses the valve closing spring and lifter arm in its outer part and has a fuel line connection to its inner part, and means for preventing transmission of dangerous pressure from the inner to the outer part.
- An valve of the kind described comprising a housing, a valve member therein, a hollow bushing surrounding said member and separating the inner and outer parts of

said housing and a check valve in said bushing adapted to prevent transmission of dangerous pressure from the inner to the outer part of the housing.

- 5 4. An injection valve for injection type engines, comprising a housing, a valve member therein, means for producing a restricted

passage between the inner and outer parts of said housing and a sleeve on the valve member for closing said passage.

10

In testimony whereof, I have signed this specification.

WALTER SCHENKER.
